(57) **CLAIM**

The ornamental design for a hydrant handle, as shown and described.

DESCRIPTION

FIG. 1 is a perspective view of the hydrant handle showing my new design;

FIG. 2 is a top plan view thereof;

FIG. 3 is a front elevational view thereof;

FIG. 4 is a right side view thereof;

FIG. 5 is a bottom view thereof; and,

FIG. 6 is a perspective plan view thereof.

The broken lines shown in FIG. 6 are for illustrative purposes only and form no part of the claimed design.
